SAFETY APPARATUS FOR ELEVATORS

Robert Neuschotz, New York, N. Y.

Application December 9, 1930, Serial No. 501,013

8 Claims. (Cl. 187—89)

This invention relates to safety apparatus for elevators.

An object of this invention is to provide an elevator equipped with a safety or emergency brake, having highly improved means for actuating the brake when the speed of the car becomes excessive. In accordance with my construction, means is provided for automatically hitching a brake actuating member carried by 10 the car to a member fixed within the shaft, whereby the actuating member is tensioned as the car continues the drop for setting the brake.

A further object of this invention is to provide elevator apparatus of the character described 15 having means for automatically breaking the circuit for the hoisting motor simultaneously with the actuation of the safety brake.

A still further object of this invention is to provide manually controlled means for actuating 20 my improved safety brake actuating mechanism.

Another object of this invention is to provide a compact and rugged apparatus of the character described, which shall comprise comparatively few and simple parts, be easy to install, relatively 25 inexpensive to manufacture, positive in operation and withal practical and efficient to a high degree in use.

Other objects of this invention will in part 30 be obvious and in part hereinafter pointed out. The invention accordingly consists in the features of construction, combinations of elements, and arrangement of parts which will be exemplified in the construction hereinafter described, and of which the scope of application will be indicated in the following claims.

In the accompanying drawing, in which is shown one of the various illustrative embodiments of this invention,

Fig. 1 is a side elevational view of an elevator 40 equipped with a safety brake and actuating mechanism embodying my invention;

Fig. 2 is a cross-sectional view taken on line 2—2 of Fig. 1;

Fig. 3 is an enlarged, elevational, detail view 45 of the means for attaching the actuating member to the fixed member, showing the position of the parts with the actuating member attached to said fixed member; and

Fig. 4 is a diagrammatic view of the elevator 50 and the safety apparatus after actuation of the safety brake.

Referring now in detail to the drawing, 10 designates a car supported by a car sling 10a and adapted to be lifted and lowered by means of cables 11 extending over a traction sheave 12

driven from any suitable motor (not shown). The opposite end of the hoisting cable may be connected to a counter balance weight 13 of any suitable construction. The car sling 10a is guided by a pair of guide rails 15 and 16 disposed within the elevator shaft and fixed to a pair of opposite walls 17 and 18 of said shaft, respectively. The guide rails 15 and 16 are preferably of T-shaped cross-section and comprise heads 15a and 16a and webs 15b and 16b respectively.

Attached to the underside of the car 10 is a safety brake device of usual construction, here shown for the purpose of illustration only, in the form of a drum 19 rotatably mounted on suitable 70 brackets 20 fixed to the underside of the car. A pair of coaxial oppositely extending screw threaded members 22, 23 are provided with a screw threaded connection to the drum 19 whereby rotation of the drum will cause the screw threaded 75 members to move inwardly toward each other or outwardly away from each other in the manner of a turnbuckle, depending upon the direction of rotation of said drum. Said screw threaded members 22, 23 are provided with outwardly 80 tapering heads 22a, 23a at the outer ends thereof for the purpose hereinafter appearing.

Extending downwardly from the underside of the car on each of the opposite sides thereof, are a pair of spaced pins 24 to which there are pivoted 85 jaws 25, 26 symmetrically disposed with respect to one another and having arms 25a, 26a respectively, adapted to engage opposite sides of one of said tapering heads 22a or 23a of the screw threaded members 22, 23. The jaws are further 90 formed with arms 25b, 26b adapted to contact opposite sides of one of the webs 15b or 16b.

It will now be seen that as the drum is rotated in a direction for drawing the screw threaded members inwardly toward one another, the tapering heads 22a, 23a will cause pivotal rotation of the jaws 25, 26 and pressure of the arms 25b, 26b against the webs of the guide rails for braking the downward movement of the car.

Means is provided for rotating the drum 19 and 100 actuating the safety brake mechanism. To this end there is fixed to the top of the car a bracket 30 having a pair of bearing members 31, 32 for rotatably mounting a pair of sheaves 33, 34. A safety cable 35 disposed longitudinally of the 105 elevator shaft, is attached at the upper end thereof to a rod 36 extending above a cross beam 37 disposed at the upper end of the elevator shaft. The rod 36 is provided with a screw threaded portion 37 carrying a nut 38. The rod 36 further 110

more extends through a suitable opening in a plate 39 fixed to the beam 37 and interposed between said plate 39 and the nut 38 is a coil compression spring 40, a suitable washer 41 being interposed between the upper end of the spring 40 and said nut 38. The spring 40 allows a slight downward yielding movement of the safety cable 35. The cable 35 extends around the underside of the sheave 34, then up and over the sheave 33, and then downwardly on the opposite side of the car sling 10a, the lower end portion 35b of the cable extending through a safety cable guide 42 fixed to the wall 17. A tension weight 43 is preferably attached to the lower end 44 of said cable. It will be seen that during the ordinary travel of the car, the sheaves 33, 34 are rotated by the cable 35.

For rotating the drum 19, there is provided a brake operating or actuating member, here shown in the form of a cable 45, wound about the drum 19 and extending upwardly toward the upper end of the car.

Means is provided for hitching the brake actuating cable 45 to the safety cable 35 automatically upon increase of speed of the dropping car 10 beyond a predetermined point. To this end, the bracket 30 is formed with a horizontal extension 46 provided with a vertical slot 47, and a second vertical slot or opening 48 adjacent thereto. Bracket 30 is provided with another extension 49 provided with a vertical opening 50 aligned with said opening 48. Slidably mounted within said aligned openings 48, 50 is a vertical rod 51 having a lug 53 attached thereto and extending inwardly therefrom, adjacent the rim of the sheave 34. The lug 52 is adapted to contact the upper side of the extension 49 at the opening 50 thereof to limit the downward movement of the rod. For the purpose hereinafter to appear, the lower end 53 of the rod 51 extends below the extension 49, and the upper end 54 extends above the extension 46. Slidably mounted within the opening 47, and supported on the extension 46 of the bracket 30 is a member 60 having a vertical wall portion 61 and a horizontal extension 62 at the upper end thereof, said extension being formed with an opening 63. Pivoted to said member 60 as on a horizontal pin 65 is a cammed member 66 having a cammed surface 67. Attached to a pin 68 projecting from the cam member 66 on one side of the pivoted pin 65 is the upper end 69 of the safety brake operating cable 45. Pivoted to the upper end of the cam member 66 as at 70 is a rod 71 loosely extending through the opening 63 in said extension 62. Attached to the lower end of said rod, is a plate 72 and interposed between said plate 72 and said extension 62 is a strong coil compression spring 75. Projecting from said cam member 66 is a pin or projection 76 adapted to be disposed directly above said rod 51, said projection being furthermore substantially aligned with the pivot pin 65 and the pin 68, said pivot pin being disposed between the pin 68 and the projection 76.

It will be noted that a line connecting the pivot pin 70 for the rod 71 with the pivot point 65 is substantially at right angles to a line passing through the points 67, 65, 76.

The cable 35 extends between the vertical wall portion 61 of the member 60, and the cammed rim or surface 67 of the cam member 66. In the position shown, in Fig. 1, the low portion of the cam is disposed adjacent the cable 35, and sufficient clearance is provided between the cam member and the backing wall 61 to permit the

elevator to be lifted or lowered without interfering with the safety cable 35.

In Fig. 1, the rod 71 extends toward one side of the pivot point 65 and is substantially aligned with the projection 76 for maintaining the cammed member in non-gripping position. Pivoted within the sheave 34 in any suitable manner, as on diametrically disposed pins 80 and 81, are governor members 80a and 81a adapted to fly outwardly upon rotation of the sheave during travel of the car. The governor members 80a and 81a are adapted to fly outwardly when the car is lowered and a pair of tension springs 82, 83 suitably connected to said members retard the outward movement thereof. Said governor members are further provided with heads 84, 85 at the outer ends thereof for the purpose hereinafter appearing.

Upon increase of speed of the car, as for example, should the hoisting cable break, beyond a predetermined point, either the head 84 or 85 will impact the underside of the lug 52 for lifting the rod 51. The upper end 54 of the rod will then strike the projection 76 and cause rotation of the cam member 66 in a counterclockwise direction, looking at Fig. 1. This rotation of the cam will bring the high side of the cam into contact with the cable 35 for pressing, wedging or clamping the same against the vertical wall 61. The pivot point 70 will also move past the dead center for bringing the lower end of the rod on the opposite side of the pivot point 65, whereby the rod will substantially point toward the projection 68 and the compression spring 75 will retain the cam in clamping or gripping position and will also tend to further rotate the cam member in a counterclockwise direction for increasing the frictional contact between the cam member and the safety cable for pressing the same tightly against the backing member 61. This movement causes hitching or attachment of the upper end 69 of the safety brake operating cable 45 to the safety cable 35. The member 60 upon being fixed to the safety cable 35 is lifted out of the opening 47 as the car continues to descend. Fixing the upper end of the cable 45 to the cable 35 will cause the drum 19 to be rotated in a direction for drawing the screw threaded rods 22, 23 toward one another, and clamping the jaws 25, 26 to the guide rails 15, 16, and braking the movement of the car.

It will be noted that as the pull on the cable 45 increases, during the unwinding operation thereof, the grip of the cam member 66 on the cable 35 increases, said cam being maintained in clamping position by pressure of the spring 75. When the cable 35 is gripped, the spring 40 will be compressed permitting a slight yielding movement. After the spring 40 is compressed however, the cable 35 becomes fixed and stationary with respect to the dropping car.

Manually controlled means is provided for hitching the safety operating cable 45 to the cable 35 in case of emergency. To this end a lever 90 is pivoted to the bracket 30 and attached to one end 91 of said lever is a pull chain 92 having a handle 93 extending within the car 10. The opposite end 94 of said lever is disposed directly beneath the lower end 53 of the rod 51. Thus, a pull on the handle 93 will cause the lever to push the rod 51 upwardly for rotating the cam member to the position shown in Fig. 3.

Means is further provided for automatically breaking the circuit for the hoisting motor simultaneously with the hitching of the brake operating cable 45 to the safety cable 35. To said

end a bracket 100 is fixed to the said supporting beam 37 at the upper end of the shaft, said bracket comprising a pair of upwardly extending members 101 and 102. Pivoted to said member 101 is an angle shaped switch member 103 having a finger 104 extending adjacent the screw threaded rod 37. Said member 103 further comprises an upwardly extending finger 104a to which there is connected a movable contact member 105 connected to a conductor 106 leading to one pole of the motor. Attached to the portion 102 of the bracket 100 is a fixed contact member 107, connected to a conductor 108 leading to the other pole of the motor in any suitable manner (not shown). Pivoted to the upper end of the member 101 of the bracket 100 is a catch finger 109 having a hook portion 110 resting on the upper end of the finger 104a. A tension spring 11 attached at one end thereof to the bracket 100 and at the other end thereof to the angle shaped switch member 103 normally maintains the contact 105 in engagement with the contact 107 whereby the motor circuit is complete. Screwed to the upper end of the rod 37 are a pair of lock nuts 115 between which there is interposed a plate or finger 116 disposed above the finger 104. Thus, when the upper end of the cable 45 is hitched to the cable 35, a strong downward pull is exerted on the cable 35 for compressing the spring 40 and moving the rod 37 a short distance downwardly. This movement of the rod 37 causes the finger 116 to strike the finger 104 and rotate the switch 103 for breaking the contact between the contacts 105 and 107. During this movement, the hooked head 110 of the catch 109 drops for engaging the upper end of the finger 104a and preventing movement of the switch 103 into switch closing position.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth, or shown in the accompanying drawing is to be interpreted as illustrative and not in a limiting sense.

Having thus described my invention, I claim as new and desire to secure by Letters Patent:

1. In combination, an elevator car, a car brake, means for actuating said brake comprising a member operatively attached to said brake and adapted to actuate said brake upon being pulled, a member removably carried by said car and connected to said first member, a sheave carried by said car, means for rotating said sheave at a speed proportional to the speed of movement of said car, and means controlled by the speed of said sheave for fixing said second member against movement for pulling said first member as said car descends, to actuate said brake.

2. In combination, an elevator car, a car brake carried by said car, a sheave mounted on said car, a flexible member attached within the elevator shaft, adapted to rotate said sheave during movement of said car, and means for actuating said brake comprising a member carried by said car and operatively connected to said brake and adapted to actuate said brake upon being pulled, and means controlled by the speed of rotation of said sheave for hitching a portion of said last named member to said first named member for pulling said last named member as the car descends, for actuating said brake.

3. In combination, an elevator shaft, an elevator car movable within said shaft, a car brake carried by said car, a flexible member attached to said brake and adapted to actuate said brake upon being tensioned, a sheave rotatably mounted on said car, a second elongated, flexible member attached at the upper end thereof within said shaft, engaging said sheave for rotating the same as the car moves within said shaft, and clamping means fixed to said first flexible member and controlled by the speed of rotation of said sheave for clamping said first flexible member to said second flexible member for tensioning said first flexible member to actuate said brake.

4. In combination, an elevator car, a sheave carried by said car, a cable attached at its upper end within the elevator shaft and wound on said sheave for rotating the same during movement of the car, a member removably mounted on said car, having a portion disposed adjacent to and on one side of said cable, a car brake and means for actuating said brake, said means comprising a cammed member pivoted to said removable member and disposed on the other side of said cable, a member connected to and adapted to actuate said brake attached to said cammed member, and means associated with said sheave for rotating said cammed member for clamping said cable against said portion of said removable member, whereby said brake actuating member is hitched to said cable for actuating said brake as the car continues to descend.

5. In combination, an elevator car, a brake including a rotatable drum, means for actuating said brake upon rotation of said drum, a member wound about said drum adapted to rotate the same, an elongated member adjacent said car, said car being adapted to move relatively to said elongated member, and means for automatically attaching said wound member to said elongated member for rotating the drum and actuating said brake, said means comprising a member removably carried by said car, means on said removable member adapted to grip said elongated member, said wound member being connected to said removable member, and speed controlled means for actuating said gripping means into gripping position, said last named means comprising a sheave rotatably mounted on said car, said elongated member being associated with said sheave for rotating the same.

6. In combination, an elevator car, adapted to be lifted and lowered within an elevator shaft, a car brake carried by said car, including a rotatable drum, means for actuating said brake upon rotating said drum, a cable wound about said drum adapted to cause rotation thereof, a second cable attached at the upper end thereof at the upper end of the shaft and extending longitudinally of said shaft, and means for automatically attaching said first cable to said second cable, said means comprising a sheave rotatably mounted on said car, said second cable being wound on said sheave for rotating the same as the car is lifted and lowered, a member removably mounted on said car having a wall portion disposed on one side of said second cable, a cammed member rotatably mounted on said removably mounted member disposed on the other side of said second cable, the free end of said first cable being attached to said cammed member and being adapted upon rotation thereof to clamp said second cable to said wall portion, a rod slidably mounted on said car adapted to rotate said cammed member, a governor mounted on said sheave, said
